UNITED STATES PATENT OFFICE.

DAVID W. HAWKSWORTH, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR ROOF.

Application filed March 13, 1922. Serial No. 543,282.

The invention relates to car roofs of that type known as "rigid" roofs, in which the roofing sheets are attached to each other without provision for relative movement.

- 5 Among the objects of the invention are; first, to obtain a construction in which the the roofing sheets are formed from rectangular blanks, thereby avoiding waste of metal; second, to obtain a rigid trussing 10 of the roof sheets without the use of separate carlines, and; third, to simplify the construction. With these objects in view the invention consists in the construction as hereinafter set forth.

15 In the drawings:

Figure 1 is a plan view of one-half the width of the roof;

Figure 2 is a cross-section;

Figure 3 is a side elevation;

20 Figure 4 is a cross-section on line 4—4 of Figure 1;

Figure 5 is a cross-section on line 5—5 of Figure 1;

25 Figures 6 and 7 are respectively a plan and vertical section showing a modified construction forming a ventilated roof;

Figures 8, 9 and 10 are cross-sections showing modified constructions at the eaves.

30 My improved roof may be applied to any suitable construction of car frame, but as shown, A are wooden side plates of the car frame, B a metallic angle strip secured to said side plate and having an outwardly extending eaves flange angled to the slope of 35 the roof. C is the siding of the car body and D a Z-bar strip having one flange clamped between the angle B and the plate A and the other overlapping the siding to form a fascia or protection for the upper 40 ends thereof. D' are bolts for securing the angle bar B to the plate A.

45 My improved roof consists essentially of alternate plates R and S, which are arranged respectively in upper and lower planes and which are secured to each other by overlapping downturned and upturned flanges riveted or otherwise rigidly secured to each other. Each of these plates is fashioned from a rectangular blank which is 50 pressed to form, in the case of the upper plane sheets, downturned perpendicular flanges E terminating in laterally extending flanges F for overlapping the lower plane

sheet. In the same manner the lower plane sheets are pressed to form perpendicular upstanding flanges E' terminating in outwardly laterally extending flanges F' which overlap the upper plane sheets. The perpendicular flanges E and E' are preferably slightly tapered from the ridge towards the 55 eaves and near to the eaves are curved to merge into a common plane adjacent to the lateral flange of the angle bar B. This tapering and curving of the flanges E and E' results in the corresponding flaring or increase in width of the lateral flanges F and F', inasmuch as the sheet is pressed from a rectangular blank. As a consequence, at the eaves there is a considerable overlap of the adjacent sheets which lessens in passing 60 from the eaves to the ridge.

65 In assembling the roof the sheets are successively placed upon the plane extending from eaves to eaves and the eaves flanges G are riveted to the outwardly extending flanges of the angle bar B. There is also provided a downturned eaves flange H which forms a weatherproof joint. Between the eaves the sheets are secured to 70 each other by riveting the adjacent perpendicular flanges E and E'. The running board I is mounted upon the roof by means of angle bars J, the vertical flanges of which 75 may be secured by the same rivets employed for securing the flanges E and E', while the running boards are bolted to horizontal flanges.

80 In the completed structure, the greater part of the metal of the plates being equally distributed between two parallel planes, a strong truss is formed for sustaining roof loads. Also the overlapping of the sheets, which increases from the ridge to the eaves, further reinforces the structure. At the same time, a certain degree of flexibility is 85 imparted to the structure by reason of the vertical flanges and while these flanges are rigidly secured to each other, thereby making a weatherproof joint, they will still yield to take care of excessive shocks.

90 In the modified construction shown in Figures 6 and 7, ventilation is provided. This is formed by apertures K through the overlapping flanges E and E', which 95 openings are weatherproofed by the running boards and the supporting angle flanges 100.

therefor. As shown, these angle flanges J' have struck-out portions J^2 therein which are riveted to the flanges E and E' , while intermediate these struck-out portions the portions J^3 are spaced from the flanges E . The apertures K are located adjacent to these spaced portions J^3 and are therefore guarded thereby so as to effectually exclude the weather, while permitting free circulation of air. Preferably an outwardly struck flange K' surrounds the aperture K and serves to prevent the seeping of water along the flange E and into said aperture.

The spacing at the running-board supporting brackets from the flanges E' has the additional advantage that it prevents the forming of the crevice in which dirt could lodge and which, by saturating with moisture, will tend to rust out the sheets. The bearing portions J' are so limited in area and are so tightly secured by the rivets as to avoid forming a crevice as just described.

As shown in Figures 8, 9 and 10, instead of forming the side plate of the car of wood, as shown in Figure 5, I have formed such side plates of metallic bars. Figure 8 shows an angle bar L having its laterally projecting flange at the angle of the pitch of the roof. Figure 9 uses a Z-bar side plate M , to which the angle flange B is attached. Figure 10 shows another Z-bar sideway N differently arranged. All of these modified constructions are, however, the same in their attachment to the roof.

35 What I claim as my invention is:

1. A car roof comprising alternate roofing sheets having their bodies arranged in spaced planes, and overlapping angular flanges projecting from said sheets rigidly secured to each other.

2. A car roof comprising alternate roofing sheets arranged respectively in upper and lower planes, downturned and upturned side flanges on the respective sheets arranged adjacent to each other, and flanges projecting laterally from said side flanges adjacent to the sheet in the other plane.

3. A car roof comprising alternate roofing sheets arranged respectively in upper and lower planes, said sheets being provided respectively with downturned and upturned side flanges lying adjacent to each other and terminating in laterally extending flanges, each adjacent to the sheet in the other plane, said upper plane sheets being fashioned to merge into the lower plane at the eaves.

4. A car roof comprising alternate sheets arranged respectively in upper and lower planes, said upper plane sheets being fashioned to lie adjacent to the lower plane at the eaves, side flanges for said sheets lying adjacent to each other, each terminating in a laterally projecting flange adjacent to the plane of the adjacent sheet, said side

flanges being riveted to each other and said eaves flanges being rigidly secured to the car frame.

5. In a car roof, the combination with a car frame having side plates and angle bars secured to said side plates with outwardly extending lateral flanges, alternate roofing sheets extending from eaves to eaves and respectively in upper and lower planes, the upper plane sheets being fashioned to merge into the lower plane at the eaves and all of said sheets overlying said angle bars and provided with down-turned eaves flanges, side flanges for said sheets lying adjacent to each other and each terminating in a laterally extending flange adjacent to the plane of the adjacent sheet, and rivets connecting said side flanges to each other and said sheets to said angle bars at the eaves.

6. A car roof comprising a car frame having side plates, angle bars secured to said side plates and having outwardly extending flanges, alternate roofing sheets extending from eaves to eaves and lying respectively in upper and lower planes, the upper plane sheets being fashioned to merge into the lower plane at the eaves and overlying said angle bar, terminating in down-turned eaves flanges, side flanges for said sheets perpendicular to the planes thereof and lying adjacent to each other, each of said flanges terminating in a laterally extending flange adjacent to the plane of the adjacent sheet, rivets for securing said sheets to said angle bar and for securing said side flanges to each other, and saddles or bracket supports for the running board secured to said side flanges by the rivets securing said flanges to each other.

7. A car roof comprising alternate sheets respectively in upper and lower planes and extending from eaves to eaves, said sheets being arched towards the ridge and the upper plane sheets being fashioned to merge into the lower plane at the eaves, each of said sheets being formed of a rectangular blank having side flanges perpendicular to the plane of the sheet and terminating in laterally extending flanges lying adjacent to the plane of the adjacent sheet, said perpendicular flanges being tapered from the ridge towards the eaves and said lateral flanges being correspondingly increased in width at the eaves, and means for rigidly attaching the perpendicular flanges of said sheets to each other and all of said sheets to the eaves.

8. A ventilated car roof comprising roofing sheets lying in spaced planes, connected by intermediate vertically extending portions, said vertical portions being apertured to provide ventilation.

9. A car roof comprising roofing sheets lying in spaced planes, connected by intermediate vertical portions having a ventilating aperture therein, and a guard for said

ventilating aperture forming a weather-proofing means therefor.

10. A ventilating car roof comprising roofing sheets lying in spaced planes connected by intermediate vertically extending portions having an aperture therein, a running-board saddle having a portion spaced from said apertured portion to form a weatherproofing guard therefor.
11. A car roofing comprising roofing sheets lying in spaced planes connected by vertically extending overlapping flanges, said flanges being apertured, and a running-

board saddle secured to said flanges and having a portion spaced therefrom for guarding said ventilating aperture.

12. A car roofing comprising roofing sheets lying in spaced planes with vertically extending overlapping flanges intermediate said planes, said flanges being apertured, and a running-board saddle having a portion rigidly attached to said flanges and a portion spaced from and overlying said apertures to form a guard therefor.

In testimony whereof I affix my signature.
DAVID W. HAWKSWORTH.
